UNITED STATES PATENT OFFICE

JOSEPH GRANAT, OF SAN FRANCISCO, CALIFORNIA

DESIGN FOR A FINGER RING

Application filed May 19, 1931. Serial No. 39,903. Term of patent 3½ years.

To all whom it may concern:

Be it known that I, JOSEPH GRANAT, a citizen of the United States of America, residing at San Francisco, county of San Francisco, and State of California, have invented a new, original, and ornamental Design for Finger Rings, of which the following is a specification, reference being had to the accompanying drawing, forming a part thereof.

The figure is a perspective view of my design.

I claim:

The ornamental design for a finger ring substantially as shown.

JOSEPH GRANAT.
